UNITED STATES PATENT OFFICE

GEARY F. STEWART, OF NORWOOD, OHIO, ASSIGNOR TO THE KINGERY MANUFACTURING COMPANY, OF CINCINNATI, OHIO, A CORPORATION OF OHIO

DESIGN FOR A POPCORN POPPER

Application filed May 23, 1932. Serial No. 43,880. Term of patent 14 years.

To all whom it may concern:

Be it known that I, GEARY F. STEWART, a citizen of the United States, residing in Norwood, in the county of Hamilton and State of Ohio, have invented a new, original, and ornamental Design for a Popcorn Popper, of which the following is a specification, reference being had to the accompanying drawings forming part thereof.

In the drawings:

Figure 1 is a front perspective view of the article, showing my new design.

Fig. 2 is a rear perspective thereof on a slightly larger scale.

The distinctive features of the design are the circular central portion in a case having the angular plane surfaces at the top, with the top trim panel conforming to the top of the casing substantially as shown, and from the rear the same relationship taken together with the completely enclosed, rounded elements in an offset relation to the center of the case, and mounted on a projecting support substantially as shown.

I claim:

The ornamental design for a popcorn popper substantially as shown and described.

GEARY F. STEWART.
